UNITED STATES PATENT OFFICE.

LOUIS LIPP, OF CINCINNATI, OHIO.

WATER-CLOSET SEAT.

SPECIFICATION forming part of Letters Patent No. 499,026, dated June 6, 1893.

Application filed January 31, 1893. Serial No. 460,359. (No model.)

To all whom it may concern:

Be it known that I, LOUIS LIPP, a citizen of the United States, residing at Cincinnati, in the county of Hamilton and State of Ohio, have 5 invented certain new and useful Improvements in the Construction of Water-Closet Seats and Similar Structures; and I do declare the following to be a full, clear, and exact description of the invention, such as will enable 10 others skilled in the art to which it appertains to make and use the same, reference being had to the accompanying drawings, and to the figures of reference marked thereon, which form a part of this specification.

15 This invention relates to construction of wooden structures where a number of smaller boards are joined together edgewise to form a larger one, which larger one is then to be perforated or contains a large opening designed for some special purpose. The particular kind of structures here understood will be more distinctly referred to in the following specification which contains a full description of my invention, the same being also 25 particularly pointed out in the claim at the end thereof and its construction illustrated in the accompanying drawings in which—

Figure 1 is a top, Fig. 2 an under side, and Fig. 3, a central longitudinal section of a water-closet seat embodying my invention.

30 I have in view here particularly the construction of water-closet seats, but any similar device containing a large opening, like cistern- or man-hole covers and where they are 35 made of wood, falls within the scope of my invention.

The necessary width in water-closet seats is generally attained by gluing a number of boards together as shown in Figs. 1, and 2, 40 where boards 4, 5, and 6, are joined together to form the seat complete.

45 For the sake of appearance it is desirable that the grain of all the individual pieces should run in the same direction, whereby however the grain or longitudinal fibers of pieces 6, are very much shorter, which for obvious reasons lessens very much the strength and stability of these pieces. Where such

pieces are subject to moisture, they necessarily warp and in their weakened structural 50 condition are not able to withstand the strain imposed by such warping and often crack, ruining thereby the whole seat. This makes it necessary that these seats are strengthened in a manner to protect their weaker portions, 55 which is usually done by cleats, strips, or bolts connected to and sunk into the wood of the seat, running lengthwise across the grain thereof. The objection to this procedure is the fact that the ends of such strips are visible at the edges of the seats and by reason of the different grain mar their appearance. As a further objection the edge of the seat becomes soon uneven, the ends of the strips or cleats protruding in the course of time 60 beyond the seat, by reason of the different degrees of shrinkage between the grain of end-wood and long-wood which meet here. This defect I overcome by strengthening only the short pieces 6, by means of strips 8, fitting 65 into dove-tailed grooves 7, at their under sides and by using the long pieces 4, and 5, to hide the ends of such strips. These latter are tightly fitted and glued into place first before pieces 4, and 5, are connected to the shorter 70 pieces, 6. Thus I strengthen the seat without disturbing the grain on its top or edges and no joints, or grain running in different directions are visible.

I claim—

A wooden water-closet seat when constructed of a number of shorter and longer pieces of wood as 6, 6, 4, and 5, and the grain of which at its top and edges should all be intact and run in one direction, having its shorter pieces 85 6, strengthened by strips 8, dove-tailed into their under side crosswise to their grain and having its longer pieces 4, and 5, connected to these shorter pieces and left intact, whereby 90 they hide the ends of strips 8.

In testimony whereof I affix my signature in presence of two witnesses.

LOUIS LIPP.

Witnesses:

SAMUEL M. QUINN,
C. SPENGEL.
